UNITED STATES PATENT OFFICE.

GEORGE HENRY WHEARY, OF RACINE, WISCONSIN.

DESIGN FOR A CORNER DOWEL.

Application filed January 26, 1923. Serial No. 4,998. Term of patent 7 years.

To all whom it may concern:

Be it known that I, GEORGE HENRY WHEARY, a citizen of the United States, residing at Racine, in the county of Racine and State of Wisconsin, have invented new, original, and ornamental Design for Corner Dowels, of which the following is a specification, reference being had to the accompanying drawing, forming part thereof.

The drawing is a perspective view of a corner dowel embodying my design.

I claim:

The ornamental design for a corner dowel, as disclosed herein.

GEORGE HENRY WHEARY.
